HANGER BRACKET

Willis Griffin, 402 22nd St., Boulder, Colo. 80302

Filed June 16, 1966, Ser. No. 2,704

Term of patent 14 years

(Cl. D54—1)

FIG. 1 is a perspective view of the hanger bracket depicting my new design, showing portions of skis in dotted lines for illustrative purposes only.

I claim:

The ornamental design for a hanger bracket, as shown and described.
